SYRINGE NOZZLE OR TUBE

Filed April 23, 1927

FIG. 1.

FIG. 2.

August von Borosini

Inventor:

by *A. M. Gandy*
Atty

UNITED STATES PATENT OFFICE

AUGUST VON BOROSINI, OF LUGANO, SWITZERLAND

SYRINGE NOZZLE OR TUBE

Application filed April 23, 1927, Serial No. 186,142, and in Germany April 28, 1926.

More particularly this invention is concerned with a nozzle or tube to be introduced into cavities of the human body for purposes of permanently applying the syringe in reclined position of the patient.

Heretofore a permanent treatment by means of a syringe could only be carried out by the aid of complicated and expensive constructions; in addition to this, the application of known apparatus of this kind had been connected with great inconveniences and required a permanent staff of helping and supervising persons.

By my present invention it will be possible to carry out a permanent washing, rinsing or medical treatment of cavities of the human body such as for instance of the bladder, the vagina or the rectum in a simple and convenient manner in reclined position of the patient. The apparatus according to my invention may of course be also employed for veterinary purposes, for which purposes the apparatus is properly modified. The main difficulty in carrying out such treatments and especially treatments for some longer periods of time had heretofore consisted in the proper fastening of the syringe tube. Heretofore the syringe tube had either to be kept by hand or fixed in proper position by means of complicated bandages, dressings or the like. Syringes of such construction require constant supervision in order to prevent the tube from slipping out of the organ to be treated by action of pressures which are exerted upon the tube after being introduced into said organ. The apparatus according to my invention is designed to avoid these disadvantages which arise especially in case of intestinal and vaginal treatment. For this purpose the tube or nozzle of the syringe is properly constructed by providing besides the front fastening eyes or lugs which are positioned at the supply end of the tube also a further rearwardly positioned eye or lug which is arranged upon a preferably resilient clip mounted on the syringe tube. The tube now may be applied to the patient by means of supporting ribbons which are connected with a belt and may thereby be kept at three

points distanced from each other and firmly fixed to the body of the patient. The tube which is introduced into the cavity of the body will thus be kept reliably and permanently in its proper position and prevented from sliding out of said cavity, yet retaining a certain ability of motion. The third fastening eye or lug itself may be made either resilient or rigid, and in the latter case the supporting ribbon which is fastened to said eyelet is provided with an intermediate elasical part of rubber or the like which is inserted into the supporting ribbon.

The auxiliary appliance for the syringe according to my invention consists, for the purpose of using the same for permanent treatment, of a contrivance permitting the patient to rest in reclined position during treatment, which contrivance may be placed above a closet or, above an especial slop-basin provided underneath the seat of the patient.

By means of the syringe nozzle according to my invention a permanent treatment in reclined position of the patient will be essentially simplified and needs no more to be carried out within a bath-tub, upon an operating table or upon a bed especially provided for this purpose. Furthermore my present apparatus may be conveniently placed above a closet or slop-basin in the manner of a reclining chair and may especially also be conveniently used outside of hospitals or the like.

In the drawing,

Fig. 1 is a perspective view of my new syringe nozzle or tube in connection with the belt serving for fixing said tube on the body of the patient, and

Fig. 2 a similar view showing the application of the syringe tube and its fixation for the purpose of intestinal treatment.

The syringe tube 1 is bent in an obtuse angle at the end to be introduced into the cavity of the body and is provided at its rear straight part with two oppositely positioned eyes or lugs 2, as well as with a forwardly and downwardly inclined clip 3 which is provided at its projecting end with a further lug or eye 3'. Two supporting

ribbons 5, 5' engage the said eyes or lugs 2, 2', while a supporting ribbon 5'' engages the front eye or lug 3' of the clip 3, all of said supporting ribbons 5, 5' and 5'' being connected at their upper ends to the belt 4. The clip 3 may either be resilient or rigid, the latter being assumed in the construction shown in the drawing. In the latter case the supporting ribbon 5'' is provided with an elastical part 6 of rubber or the like, as indicated in Fig. 1 of the drawing. Also said supporting ribbon 5'' may consist as whole of elastical material so that there will be in every case a certain ability of motion of the tube, said tube, however, being always safely kept in position within the cavity of the body and prevented from sliding out of the same.

As indicated in Fig. 2, the bent off end of the tube 1 is inserted into a cavity of the body, that is according to the example shown in Fig. 2 into the rectum of a patient, while the other or rear end of said tube is connected with the conduit for supplying the rinsing liquid thereto. The clip 3 with the eye or lug 3' is positioned outside of the cavity of the body intermediate the legs of the patient. The belt 4 is laid around the body of the patient, while the supporting ribbons 5, 5' and 5'', engage at their upper and lower ends the belt 4 and the eyes or lugs 2, 2' and 3' respectively. The eyes or lugs 2, 2' which are provided at the tube 1, will keep the latter in proper position with respect to the body of the patient and the cavity to be treated. In order to carry out a permanent treatment there is employed a reclining chair in the form of a ladder 7 or a similar construction 7 and 7' as shown in Figs. 3, 4, 5 and 6. This reclining chair is either connected with the closet 9 or with a slop-basin 13 or the like, which is preferably provided with a discharge cock 14. The basin 13 or closet 45 is so placed that the patient will be positioned with its seat above the slop-basin or as the case may be above the closet which serves for taking up the rinsing liquid after having been passed through the cavity to be treated.

I claim:

A syringe nozzle or tube comprising lugs provided at its end which projects from the cavity of a human or animal body during treatment, said lugs adapted to serve for the reception of a supporting ribbon, and a clip projecting during treatment from said nozzle or tube in a direction towards the rear, and a further lug provided at the end of said clip and adapted for the reception of a further supporting ribbon.

In testimony whereof I affix my signature.
AUGUST von BOROSINI.
